UNITED STATES PATENT OFFICE.

MABEL K. HATT, OF BROOKLYN, NEW YORK.

PROCESS OF PRODUCING PRINTING-PLATES.

1,162,162.

Specification of Letters Patent. Patented Nov. 30, 1915.

No Drawing.

Application filed May 9, 1913. Serial No. 766,543.

To all whom it may concern:

Be it known that I, MABEL K. HATT, a citizen of the United States, residing at Brooklyn, in the county of Kings and State 5 of New York, have invented certain new and useful Improvements in Processes of Producing Printing-Plates, of which the following is a specification.

The invention relates to a process of making printing plates photo-mechanically, and more especially to a process for producing photo-mechanically printing plates for three color work, and the invention has for its objects the production photo-mechanically of 15 color plates which are substantially correct in their color representations or color values, and which do not require a large amount of the usual after treatment or hand work which is ordinarily necessary in preparing 20 and correcting the plates for the various colors, and especially the magenta plate.

In the case of each of the color plates made with the usual color screens there is in the printings an excess or fullness of color 25 in those parts of the picture or design which contain the color complementary to the particular color the plate is printed in.

There is an excess of the color in which a particular plate is to be printed in such 30 parts of the picture as show colors which are complementary to the printing color. Also, but in a lesser degree there is an excess of the color in which the plate is to be printed in those parts of the picture which 35 may be called partially complementary to the printing color.

As an example, in the plate which is used to print the magenta color, it will be found that by pure photography there is a very 40 great excess of the magenta in the greens and that there is also an excess of the magenta, although in a lesser degree, in the greenish blues and the yellows. In other words, the plate which is made for the 45 magenta color is too full in the green of the picture in a comparatively marked degree. It is likewise too full, although in a lesser degree, in the peacock blue and allied colors of the picture, and this is likewise true with 50 respect to the yellows of the picture, although in a still lesser degree with regard to these latter.

The plate for printing the blue may be gotten very nearly correct by the use of the 55 red color filter and may be regarded as correct within practical bounds or limits, and

where this plate is out at all it will be found too full in the reds.

The plate for printing the yellows as made photo-mechanically with the violet color filter is usually not as correct as the blue. This yellow plate is too full in the violets, the purples and the blues, that is, as made by the color filter it will impart too much yellow in the print to the violet tint 65 and the purple tints and the blue tints which are built up by superimposition of one printing upon the other, and which may be considered as the secondary colors of the printings. The greatest excess in the plate 70 for the yellow will be found in the violet.

In accordance with the present invention there is provided a corrective to the light in connection with the creation of the screen figure upon the negative, whereby the excess 75 or objectionable fullness is eliminated from the negative, instead of from the printing plate itself, and furthermore, this is done in the case of the present invention by the process photo-mechanically as distinguished 80 from hand work on the plate. Thus not only is expensive corrective work on the plate avoided, but the correction is made once for all in the negative and is thus effected and completed for any desired number 85 of printing plates which may be made from that negative, whereas in the old form the corrective work in addition to being done expensively by hand has to be done for each successive plate made from the negative. 90

In carrying out the process of my invention, the subject to be reproduced is positioned or posed before the camera in the usual manner. The color filter for the complementary color to that in which the plate 95 is to be printed is employed to cut out the other colors which are not desired in the particular plate for which the negative is being made. By way of example, if the 100 plate to be made is the plate for printing the magenta, the green color filter will be used.

Before the sensitized plate in the camera a half tone screen is inserted, the rulings or tintings of which are partially light transmitting for certain light rays but impervious to other light rays. That is, the tintings or rulings are translucent and of a color which is corrective of the errors or aberrations of the plate already described. 105

Referring again to the making of the magenta plate, a half tone screen would be used

having its lines and rulings of a greenish color and having the different areas thereof of different degrees of light transmitting power. This screen will have the effect of 5 exaggerating the light action of the greens, blues and yellows in the magenta negative.

It will be understood that I thus secure a differential action at the plate and change the ratio of the various light rays which 10 have passed the color filter so as to emphasize the greens and blues and yellows in the plate and thus correct the fullness of this plate in these colors.

In making the half tone negative, I prefer 15 the employment of a direct method of color photography, either with collodion emulsion or on color sensitive gelatin dry plates. The surface of the copper or other printing plate to be made from the negative 20 may be sensitized in any of the well known ways, and the various steps of making the plate proceeded with in the usual manner only that the corrective hand work necessary for reducing the fullness of the plate, and 25 especially the magenta plate, as heretofore described, is obviated.

In carrying out the invention I prefer to use such a half tone screen as I have already described having also the features of the 30 Hatt high light screen patented to J. A. H. Hatt July 8, 1913, by United States Patent No. 1,066,611.

By the use of a medium, such as the half 35 tone screens with the translucent colored tintings or rulings, I am enabled to get the desired modified action on the surface of the printing plate. That is, the full light which is passed by the color filter, taking for instance the green color filter, is permitted 40 to act on separate, small and closely contiguous areas of the sensitized plate or negative represented by the clear glass transparent portion of the screen figures, and the green light, or a portion thereof, is permitted 45 to pass more easily in the areas or portions of the screen which are of a greenish color and which will give the necessary effect in the greens, blues and yellows as printed from the magenta plate. The office 50 or effect of the greenish half tone screen in the case of the negative for the magenta plate would be equivalent, so far as its effect 55 on the final picture is concerned, to make the greens, blues and yellows of the copy or original brighter and give them more actinic value on the negative and thus by photo-mechanical means bring the printed picture into truer relation to the copy.

Where it is desired only to correct the 60 magenta plate, the corrected half tone screen for this color may be also employed for the other colors, as it will have no effect upon the blue or yellow negatives, for the reason that the green screen is practically 65 opaque to the violet light used for the yellow

negative and the red light used for the blue negative. It will be understood therefore that by my process I modify the plate photo-mechanically to compensate for variation from the ideal colors of the actual inks obtainable for and workable in printing. 70

The printing plate is then made from the sensitized plate in the usual manner and the various printings are made upon the impression receiving material to constitute the 75 complete picture, as hereinbefore indicated.

It will be understood that while I have described the preferred manner of carrying out my process of my invention, that changes may be made therein within the 80 scope of the accompanying claims without departing from the principles of the invention.

What I do claim as my invention, and desire to secure by Letters Patent, is:

1. The process of producing a photo-mechanical printing plate for printing in colors which comprises photographing the original through a suitable color filter onto a sensitized plate which is to constitute the 90 half tone negative for the desired color and interposing before said negative an instrumentality which will change the relative action upon the plate of the various component rays of colors of the light which has passed through the color filter, and making a printing plate from said sensitized plate after it has been so exposed.

2. The process of producing a photo-mechanical printing plate for printing in colors which comprises photographing the original through a suitable color filter onto a sensitized plate and interposing before said negative an instrumentality which will change the relative action upon the plate of the various component rays or colors of the light which has passed through the color filter, and making a printing plate from said sensitized plate after it has been so exposed. 100

3. The process of producing a photo-mechanical printing plate for printing in colors, which process comprises photographing an original through a suitable color filter on to a sensitized plate which is to constitute the half tone negative for the desired color and interposing between said color filter and said sensitized plate a half tone screen having rules or tintings which permit a part of the filtered light to pass and prevent other parts thereof from passing and making a printing plate from said sensitized plate after it has been exposed. 110

4. The process of producing a photo-mechanical printing plate for printing in colors, which process comprises photographing an original through a suitable color filter on to a sensitized plate and interposing between said color filter and said sensitized plate a half tone screen having rules or tintings which permit a part of the filtered light 120 125 130

to pass and prevent other parts thereof from passing, and making a printing plate from said sensitized plate after it has been so exposed.

5. The process of producing a photo-mechanical printing plate for printing in colors which process comprises photographing an original through a suitable color filter on to a sensitized plate and acting on the filtered light between said color filter and said sensitized plate to render some of its component colors brighter with respect to the other component colors thereof, and making a printing plate from said sensitized plate after it has been so exposed.

6. The process of producing a photo-mechanical printing plate for printing in colors which process comprises photographing an original through a suitable color filter on to a sensitized plate and interposing between said color filter and said sensitized plate a screen having translucent rulings or tintings which rulings or tintings transmit to the sensitized plate certain thereon of the filtered light rays and arrest other of the filtered light rays falling thereon and making a printing plate from said sensitized plate after it has been so exposed.

7. The process of producing a photo-mechanical printing plate for printing in colors which process comprises photographing an original through a suitable color filter on to a sensitized plate and interposing between said color filter and said sensitized plate a screen having translucent rulings or tintings which rulings or tintings transmit to the sensitized plate certain thereon of the filtered light rays and arrest other of the filtered light rays falling thereon, the open spaces of the screen between the rulings or tintings transmitting all the filtered light falling thereon on to the sensitized plate, and making a printing plate from said sensitized plate after it has been so exposed.

45. 8. The process of producing a photo-mechanical printing plate for printing the magenta color in a multi-color picture, which

process comprises photographing a colored original through a green color filter on to a sensitized plate and interposing a screen between said filter and sensitized plate which has greenish translucent rulings or tintings and clear or open spaces therebetween, and making a printing plate from said sensitized plate after it has been so exposed.

50

55. 9. The process of producing a photo-mechanical printing plate for printing in colors which process comprises photographing an original through a suitable color filter, on to a sensitized plate and applying a corrective to the filtered light in connection with the creation of a screen figure upon said sensitized plate, and making a printing plate from said sensitized plate.

60

10. The process of producing a photo-mechanical printing plate for printing in colors, which process comprises filtering out one of the colors of the original, and modifying the actinic action of another of the colors upon a sensitized plate.

65

70. 11. The process of producing a photo-mechanical printing plate for printing in colors, which process comprises making a plurality of printing plates for the various colors by filtering out other colors, and varying 75 or modifying the actinic effect of the various colors in making the various printing plates.

12. The process of producing a set of mechanical printing plates for printing in superimposition in colors, which process comprises making a printing plate for each of the colors to be printed in superimposition by filtering out for each plate all but the particular color for said plate, and modifying the actinic effect of each of the said 85 colors upon its particular plate.

In testimony whereof, I have signed my name to this specification, in the presence of two subscribing witnesses.

MABEL K. HATT.
